E. G. COX

CLOTHESPIN

Filed April 5, 1922

Inventor

EDWIN G. COX

By Harry Schwartz
attorney

UNITED STATES PATENT OFFICE.

EDWIN G. COX, OF BERKELEY, CALIFORNIA.

CLOTHESPIN.

Application filed April 5, 1922. Serial No. 549,824.

To all whom it may concern:

Be it known that I, EDWIN G. Cox, a citizen of the United States, residing at Berkeley, in the county of Alameda and 5 State of California, have invented certain new and useful Improvements in Clothespins, of which the following is a specification.

My invention is an improved wire spring 10 clothes pin constructed to slip readily over the clothes line and to clamp the clothes around the line, instead of over the line like a wooden pin, thus effectively holding the clothes on the line and preventing itself 15 from slipping off the line.

Referring to the annexed drawing in which my invention is illustrated and which forms a part of this specification:

Figure 1 is an edge view of my clothes 20 pin.

Figure 2 is a side view of my clothes pin.

Figure 3 is a perspective view of the upper part of my clothes pin.

My clothes pin is made of a single piece of 25 wire 1 and includes a head loop 2 and a pair of spring clamp members 3 and 4 which are connected to the head loop by clasp loops 5 and 6 formed at the ends of said wire. The wire 1 is bent in the middle 30 to form the head loop 2 and a pair of arms 7 and 8 which extend through the loops 6 and 5 respectively. The clamp member 3 includes a pair of arms, the arm 7 and an arm 9 and a loop 10 bent in the wire 1 and joining the lower ends of said arms, which arms 35 converge slightly upwardly. The upper portion of arm 9 extends in back of arms 8 and through the loop 5 near its upper end and its upper end portion 11 is bent across the rear of the lower part of loop 2 and has the 40 loop 6 formed at its extremity. The clamp member 4 includes a pair of arms, the arm 8 and an arm 12 and a loop 13 bent in the wire 1 and joining the lower end of said arms, which arms 45 extend substantially parallel to each other and their lower portions and the loop 13 are positioned within the arms 7 and 9 and the loop 10 respectively, so that the lower portion of clamp member 4 may be normally sprung within the lower 50 part of clamp member 3. The upper por-

tion of arm 12 extends in front of arm 7 and through loop 6 near its upper end and its upper end portion 14 is bent across the front of the lower part of loop 2 and has the loop 55 5 bent on its upper end. The lower portions of the arms 7 and 9 are bent inwardly at an angle, forming jaws 15 and the loop 10 is bent outwardly at an angle from said jaws. The lower portion of the arms 8 and 12 are 60 bent inwardly at an angle, forming jaws 16 and the loop 13 is bent outwardly at an angle from said jaws.

In placing the pin over the clothes on the line the inner sides of the loops 10 and 13 65 engage the clothes on the line and with a cam action spread the clamp members 3 and 4 apart against the spring tension of the clasp loops 5 and 6 between the upper ends of said members and head loop 2, so that 70 the jaws 15 and 16 slip over and under or around the line, thus securely holding the clothes and the pin on the line.

Having described my invention, I claim:

1. A wire clothes pin including a head 75 loop and a pair of spring clamp members, the wire being bent in the middle to form a head loop and a pair of downwardly extending arms forming one of the arms of the clamp members respectively, each of said 80 arms being bent at its lower end into a loop of a clamp member and upwardly into an upwardly extending arm of said clamp member, the upwardly extending arms of said clamp members extending respectively 85 in front of and behind the downwardly extending arms of the other clamp members, the upper end portion of the upwardly extending arm of each clamp member being bent across the lower part of said head loop 90 and bent at its end in a loop around the downwardly extending arm of said clamp member and the upwardly extending arm of the other clamp member, the lower part of the arms of each clamp member being bent 95 inwardly at an angle, forming jaws, and the loops at the lower ends of said clamp members being bent outwardly at an angle.

2. A clothes pin formed of a single piece of wire and having a U shaped head loop, 100 spring clamp members extending below the said head loop, the ends of the wire being

bent across and around the ends of the U and means for securing the same in place.

3. A clothes pin formed of a single piece of wire bent in the middle to form a head loop and having downwardly extending arms, said arms being bent inwardly and upwardly to form bottom loops and being

again bent inwardly at their upper ends so that the ends of the wires are looped about the lower portion of the head loop and also about each other to form a resilient connection between said arms.

In testimony whereof I affix my signature.

EDWIN G. COX.
